UNITED STATES PATENT OFFICE.

WILLIAM BLACKMORE, OF CLEVELAND, OHIO, ASSIGNOR TO THE NATIONAL MALLEABLE CASTINGS COMPANY, OF CLEVELAND, OHIO, A CORPORATION OF OHIO.

CAR-COUPLING.

1,144,024.

Specification of Letters Patent. Patented June 22, 1915.

Original application filed November 7, 1912, Serial No. 729,943. Divided and this application filed December 16, 1914. Serial No. 877,504.

To all whom it may concern:

Be it known that I, WILLIAM BLACKMORE, a citizen of the United States, and resident of Cleveland, Cuyahoga county, Ohio, have 5 invented certain new and useful Improvements in Car-Couplers, of which the following is a specification; reference being had to the accompanying drawings, in which—

Figure 1 is a horizontal section of a coupler embodying my invention and showing the parts in locked position; Fig. 2 is a section on lines II—II of Fig. 1; Fig. 3 is a horizontal section showing the parts in lock-set position; Fig. 4 is a section on lines 10 15 IV—IV of Fig. 3; Fig. 5 is a horizontal section showing the parts in knuckle-thrown position; Fig. 6 is a section on lines VI—VI of Fig. 5; Fig. 7 is a longitudinal vertical section on lines VII—VII of Fig. 2, showing the parts in locked position; Fig. 8 is a longitudinal vertical section on lines VIII—VIII of Fig. 6, showing the parts in knuckle-thrown position; Fig. 9 is a section 20 25 showing interlocked couplers during buffing, and Fig. 10 is a detail of the lock.

My invention relates to car couplers of the Master Car Builders' type; is designed to provide a coupler in which the stresses of buffing and draft shall be transmitted directly through the coupler-knuckle to the coupler-head, and which is of greater strength and durability than those now in service on railroads.

My improvements are effected by changes 30 35 in the form and construction of the coupler-head, the knuckle, the locking and knuckle-throwing members, and in the inter-action and engagement therebetween.

Referring to the drawings, 2 is the coupler-head, 3 the knuckle, 4 the lock and 5 the opener.

The numeral 6 is the knuckle-pin, of sufficiently less diameter than the knuckle-pin hole to give a clearance space α which prevents stress thereon during buffing or draft.

The cavity in the coupler-head 2 is provided with a transverse bearing wall 7 for the pulling lug 8 of the knuckle 3, and clearance spaces y , z and w are also provided 45 50 between the side face 9, the back wall 10 and the shoulder 32 of the knuckle and the walls 11, 12 and 33 respectively of the coupler-head.

The lock 4 has a head or enlarged portion

having a longitudinal flat face 13, which contacts with the front face 14 of the knuckle-tail when in locking position, and on its side opposite a corresponding flat face 15 for engagement with the wall 16 of the coupler-head. The lock has also a depending leg 17, 60 having an under-cut lock-setting surface 18 and a toe 19 adapted to coöperate with the knuckle-opener 5. Upon one side of the head of the lock and above its locking face 13 is an eye 20 for connection with the lifting link 21. At the opposite side of the head is a projection 22, which is adapted, during the opening movement, to contact with the shoulder 23 of the coupler-cavity.

The knuckle-opener 5, the trunnion 24 of 70 which is rotatably seated in the socket 25 of the coupler-head, has two arms 26 and 27. The arm 26 operates in the slot 28 on the under side of the knuckle-tail, and the arm 27 coöperates with the leg 17 of the lock. 75 The locking lug 29 on the bottom of the opener 5 permits its removal from the coupler-head only when the knuckle has been removed, since the opener must be rotated so that it will register with the slot 30 at the 80 side of the socket 25 and can then be lifted out. The slot 28 is located along the neutral axis of the knuckle tail, since the removal of metal from the tail along this line will least affect its strength.

The operation of my device is as follows: When it is desired to bring the lock 4 into lock-set position, the lock is lifted by the lifting link 21, and as soon as the body of the lock clears the knuckle-tail 3, its leg 17 90 will swing to the left, because the lifting eye 20 is off center, and the under-cut surface 18 will lodge on top of the arm 27 of the opener 5, and the lock will then be in lock-set position and the cars may then be 95 drawn apart without further operation of the coupler. When it is desired to throw the coupler into open position the lock 4 is lifted by the lifting link 21 until the projection 22 on the lock strikes the shoulder 100 105 110 23 in the upper wall of the coupler-cavity, which acts as a fulcrum bearing and causes the toe 19 of the lock to be thrown transversely of the coupler-cavity against the arm 27 of the opener 5, so that the opener 5 will rotate about its trunnion 24 in its socket 25, and its arm 26 will throw the knuckle open. When the coupler is in closed position, as

shown in Figs. 1, 2 and 7, and under draft, the knuckle 3 is pulled forwardly by reason of the clearance spaces x and y and is held tight on the bearing face of its pulling lug 5 8 and the front bearing face 14 of its tail, between the bearing wall 7 of the coupler-head and the locking face 13 of the lock, and the lock is held securely against the surface 14 of the knuckle-tail by its surface 10 15, which bears against the wall 13 of the coupler-head. In bushing, the clearance spaces w , x , y and z permit the knuckle to be driven rearwardly until the back wall of the knuckle-tail bears solidly against the 15 20 25 back wall of the coupler-cavity, and the nose of the opposing knuckle will also bear against the front face 31 of the coupler, so that the bushing shock will be transmitted from coupler-head to coupler-head by solid metal, as is shown in Fig. 9. It will be seen, therefore, that in draft the stresses will be transmitted directly through the knuckle-tail to the coupler-head, and that in bushing the knuckle will have a solid bearing at the 25 30 35 back against one coupler and at the front against the opposing coupler.

The pulling lug of the knuckle tail is preferably so constructed that its pulling face is at right angles to the longitudinal axis of the coupler, and its shearing strength across the section of maximum shearing stress with reference to the strains to which it is subjected is relatively at least as great as the strength of the metal in tension 35 through the hub of the knuckle.

The present application is a division of my copending application, Serial No. 729,943, filed November 7, 1912.

What I claim is:

40 1. In a car coupler, a lock having a connection for a lifting link on its head on the side toward the longitudinal center line of the coupler, a projection on the opposite side of the head of the lock, a shoulder in the upper part of the coupler-cavity with which said projection is designed to coöperate, a leg depending from the lock, a two-armed knuckle-opener pivotally mounted in the bottom of the coupler-head, the said leg

being adapted to swing transversely of the 50 coupler-cavity and in a direction toward the rear side of the knuckle-tail, to coöperate with an arm of the opener for lock-setting and knuckle-throwing.

2. In a car coupler, a knuckle-opener pivotally mounted in the bottom of the coupler-head and having two arms, one being adapted to be actuated by the lock and the other having a lug thereon, adapted to operate in a recess in the under face of the 60 knuckle-tail, the said recess being located along the line of the neutral axis of the knuckle-tail.

3. In a car coupler, a vertically-movable lock having a depending leg adapted to 65 swing transversely across the coupler cavity, and a two-armed knuckle-opener having a pivotal bearing on the bottom of the coupler head, the said leg being adapted to seat upon said opener for lock-setting and to actuate 70 it for knuckle-throwing.

4. In a car coupler having a pivoted knuckle and a vertically movable and tilting locking device, said locking device having a head and a depending leg and a point of attachment for lifting mechanism, a fulcrum point on said lock at one side of said point of attachment, a shoulder in the coupler head against which the fulcrum point bears when it has been lifted to tilt the leg of the 80 lock transversely to actuate a knuckle throwing member.

5. In a car coupler a pivoted knuckle, a floating locking piece comprising a head adapted to transmit pulling strains therethrough and a depending leg, the said head having a longitudinally disposed fulcrum shoulder, a shoulder in the coupler head adapted to coöperate with the shoulder on the lock by a bodily vertical movement of 90 the lock to throw the leg of the lock transversely to actuate a knuckle throwing member.

WILLIAM BLACKMORE.
